DEVICE FOR REMOVING AND REPLACING
RADIATOR CAPS

Kenneth H. Chapman, Bakersfield, Calif., assignor of one-half to Michael A. Easley, Bakersfield, Calif.
Filed Jan. 11, 1965, Ser. No. 424,752
3 Claims. (Cl. 81—90)

The present invention relates to a device for removing and replacing radiator caps and more particularly to such a device which is operable from a position spaced sufficiently from the radiators to insure safe convenient manipulation of the caps.

The difficulties and hazards of removing a radiator cap from an over-heated radiator on an automobile are well known. The high pressure developed by the coolant fluid in the radiator is exerted against the cap which tends to resist rotation and removal of the cap from the radiator. It is conventional practice for the operator to grip the cap, while being protected with a cloth, glove, or the like for initial rotation of the cap to a position permitting the high pressure coolant and vapors to be released. However, this frequently causes a jet of the scalding fluid vapor to be directed toward the operator. If complete removal of the cap is attempted prior to reducing the pressure of the coolant fluid, the cap may be blown from the operator's hand, frequently causing injury to the operator or to other adjacent objects. Furthermore, the cap may be lost or inadvertently misplaced while attending the radiator or during other service operations. Failure to replace the cap permits subsequent escape of coolant fluid which, if unobserved, results in serious damage to the engine.

Therefore, it is a broad object of the present invention to provide an improved device for removing and replacing radiator caps.

Another object is to provide such an improved device which enables the operator thereof to be spaced a safe distance from the radiator during use.

Another object is to provide a device for removing and replacing radiator caps which enables the caps to be quickly and easily removed without the usual delay experienced with conventional methods and with a minimum of hazard to the operator.

Another object is to provide a device for removing and replacing radiator caps which minimizes loss or misplacement of the caps.

Another object is to provide such a device which affords a visual reminder of prior cap removal so as to insure replacement of the cap.

Another object is to provide a device of the character described which is capable of retaining a radiator cap in assembly therewith until replaced on the radiator.

Other objects and advantages of the present invention will become more fully apparent upon reference to the drawing and following description in the specification.

FIG. 1 is a side elevation of the radiator cap removing and replacing device embodying the principles of the present invention shown in operating position relative to a radiator cap of an automobile engine cooling system.

FIG. 2 is an enlarged side elevation of the device of the present invention having the handle portion thereof foreshortened for illustrative convenience and showing the radiator cap of FIG. 1 in dashed lines.

FIG. 3 is an enlarged fragmentary front elevation of the head portion of the device of the present invention as viewed in the direction of the arrows on line 3—3 of FIG. 2 with the radiator cap removed therefrom.

FIG. 4 is an enlarged bottom plan view of the head

2

portion of the device of the present invention as viewed in the direction of the arrows on line 4—4 of FIG. 2 showing the radiator cap in dashed lines.

FIG. 5 is a transverse vertical section through the head portion of the device of the present invention taken on line 5—5 of FIG. 2.

Referring more particularly to FIG. 1 of the drawing, a device for removing and replacing radiator caps employing the principles of the present invention, is generally indicated by the reference numeral 10. The cap removing and replacing device is conveniently shown and described in association with an automobile fragmentarily indicated by the reference numeral 11. The automobile is shown having a hood 12 disposed in raised position to provide access to an engine compartment 14. A conventional engine cooling system radiator 16 is disposed within the engine compartment and has a removable cap 17 providing diametrically opposed gripping ears 18.

The radiator cap removing and replacing device 10 of the present invention provides a cup-shaped cap-engaging head portion 20. The head includes an upper wall 22 and an integral depending annular side wall 23, providing an annular lower edge 24. The upper and side walls define a cap receiving recess 25 within the head 20. The side wall has a pair of diametrically opposed ear receiving slots 26 individually providing admitting portions 27 in the lower edge 24 and circumferentially extended cap retention or locking portions 28 angularly displaced therefrom. A cap locking finger 30 is formed in the side wall of the head between each of the locking portions 28 of the slots 26 and the lower edge 24. Each of the slots also provides opposite cap driving ends 31 and 32 respectively adjacent to the locking and admitting portions.

An elongated tubular handle 35 is provided for manipulating the cap-engaging head 20 of the device 10. The handle provides an arcuately curved intermediate portion 36 integrally joined to a flattened end 37. The handle includes an opposite distal end 38 which mounts a handle gripping member 40 formed of a material such as rubber, plastic, or the like affording a high coefficient of friction. The flattened end 37 of the handle is connected to the upper wall 22 of the head 20 by a pair of spaced rivets 42 and an intermediate rivet 43 extended concentrically through the upper wall. The intermediate rivet has a large diameter lower flange 45 disposed within the recess 25 of the head.

An elongated compression spring 50 is disposed concentrically within the recess 25 of the head 20. The spring has a lower cap-engaging end 52 and an opposite upper reduced diameter coiled end 54 captured between the flange 45 and the upper wall 22 of the head to hold the spring in said concentric position within the recess.

Operation

The operation of the described embodiment of the subject invention is believed to be clearly apparent and is briefly summarized at this point. The device of the present invention may be best employed for removing radiator caps from over-heated radiators such as represented by the cap 17 and the radiator 16 in FIG. 1. The device 10 of the present invention is manipulated by grasping the gripping member 40 of the handle 35 so that engagement of the head 20 is easily and conveniently accomplished at a safe distance from the radiator. The head is initially positioned in superimposed relation above the cap with the ears 18 thereof individually aligned with the ear admitting portions 27 of the slots 26. A downward force is then applied by the operator against

the handle to lower the side wall 23 of the head in circumscribing relation about the cap.

During such movement, the spring 50 is compressed, as the ears of the cap move relatively upwardly through the admitting portions of the slots. As soon as the ears pass the finger portions 30 the handle is swung in a substantially horizontal direction for rotating the cap in a clockwise direction as viewed in FIG. 4. Such rotation of the cap causes relative movement of the ears 18 into the locking portions 28 of their respective slots 26. The spring 50 provides a reaction force tending to eject the cap from the recess 25 of the head 20. However, with the ears disposed within the locking portions of the slots in the side wall, the ears are held against the fingers 30 dependably to hold the cap and head in unitary assembly. This also enables the operator to release the downward force on the handle previously required to admit the cap into the recess of the head.

Upon continued rotation of the cap, the ears 18 of the cap 17 engage the ends 31 of the slots 26 whereby further horizontal swinging movement of the gripping member 40 of the handle 35 is effective to rotate the cap 17 relative to its connection with the radiator 16 toward a released position therefrom. Upon release, the cap is dependably constrained in unitary assembly with the head 20 of the device, and any upward movement of the cap from high pressure in the radiator is easily resisted and controlled from the gripping member 40 of the handle. Also the cap remains in the described unitary assembly during servicing of the cooling system of the automobile, until it is desired to replace the cap on the radiator.

The cap 17 is easily replaced in locking position upon the radiator 16 by manipulation of the handle gripping member 40 of the handle 35. After initial placement of the cap 17, a downward force is applied by the operator against the handle frictionally to engage the ears 18 of the cap with that portion of the side wall defining the upper edge of the slots 26. The handle is then swung in a direction opposite to the direction described in removing the cap. During the initial portion of such swinging movement of the handle, relative movement between the ears of the cap may occur depending upon the magnitude of the downward force being exerted against the handle. This relative movement, however, is discontinued upon engagement of the ears with the ends 32 of the slots 26 adjacent to the admitting portions 27 thereof. Upon such engagement the cap is easily rotated during the horizontal swinging movement of the handle positively to lock the cap in position on the radiator. After the cap is firmly locked in place on the radiator, the downward force against the handle is released so that the spring 50 is effective to actuate the head 20 upwardly to eject the ears 18 through the admitting portions 27 of the slots 26.

In view of the foregoing, it is readily apparent that the present invention provides an improved device for removing and replacing radiator caps with a minimum of hazard to the operator. The device is easily connected to the radiator cap to effect its quick and convenient removal, while the operator is in a position spaced sufficiently from a radiator to insure his personal safety. Furthermore, the radiator cap is constrained in unitary assembly with the device of the present invention until replaced upon the radiator, so as to minimize loss and/or inadvertent misplacement of the cap during the period in which it is removed from the radiator.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. A device for removing and replacing a cap on a cooling system radiator with the cap having thermally conductive gripping portions comprising cap engaging means having an annular wall adapted to be disposed in circumscribing relation about the cap, said wall including a pair of opposed circumferentially extended slots to receive said gripping portions of the cap between a first admitting and ejecting position with the slots permitting angular movement of the cap engaging means relative to the gripping portions of the cap, and a second cap retentive position with the cap engaging means angularly displaced from said first position with the wall of said slots in frictional engagement with the gripping portions of the cap; resilient force means having an end mounted on said cap engaging means and an opposite end for direct engagement with said cap to maintain said cap engaging means in said retentive position relative to the cap; and elongated manipulating means connected to the cap engaging means having a distal portion for rotating the cap by an operator at a distance insuring safe removal and replacement of the cap.

2. A device for removing and replacing a cap on a cooling system radiator with the cap having thermally conductive gripping portions comprising a cap engaging member having a substantially continuous annular wall adapted to be disposed in circumscribing relation about the cap, said wall including a pair of diametrically opposed circumferentially extended slots and circumferentially extended fingers partially closing the slots to provide a first admitting and ejecting position permitting angular movement of the cap engaging member relative to the gripping portions of the cap, and a second cap retentive position with the cap engaging member angularly displaced from said first position and with said gripping portions disposed within said slots in frictional engagement with the fingers of said wall; a resilient force transmitting member having an upper end mounted on said cap engaging member and an opposite lower end for direct engagement with said cap to maintain said cap engaging means in said retentive position relative to the cap; and an elongated manipulating member connected to said cap engaging member having a distal portion for rotating the cap from a remote position insuring safe removal and replacement of the cap.

3. A device for removing and replacing a cap on a cooling system radiator with the cap providing thermally conductive opposite ear portions comprising a substantially circular cap engaging head having an upper wall and an integral depending substantially continuous annular side wall providing a lower edge with said upper and side walls defining a recess in the head and being adapted to be disposed in circumscribing relation about the cap, said side wall including a pair of diametrically opposed circumferentially extended slots and circumferentially extended fingers coextensive with said lower edge of the side wall partially closing the slots individually providing spaced admitting and locking portions alternately to permit entry of the cap into said recess of the head with said slots receiving said ears of the cap for angular movement of the head relative to the cap for positioning the ears of the cap in said locking portions of the slots in frictional engagement with adjacent portions of the fingers and the annular side wall; an elongated compression spring concentrically disposed within the recess of the head having a lower cap engaging end and an opposite upper reduced diameter end; a fastener member extended through said upper wall of the head and providing a lower flange portion mounting said upper end of the spring and an upper head end, said lower end of the spring being directly engageable with the cap when the cap is positioned within the recess to provide a retentive force to hold the cap in the recess when the ears are disposed in said locking portions of the

slots against said fingers and being effective to eject said cap from the recess when the ears of the cap are disposed in said admitting portion of the slots; and an elongated handle having a flattened inner end connected to the head by the head end of said fastener member, a curved intermediate portion extended upwardly outwardly from said upper wall of the head in coextensive relation for a portion of its length with said side wall of the head for optimum leverage and an opposite manual gripping end extended from the head for rotating said cap at a remote distance insuring safe removal and replacement of the cap.
